(57) **CLAIM**

The ornamental design for a furniture leg, as shown and described.

DESCRIPTION

FIG. 1 is a left front perspective view of a furniture leg showing my new design;

FIG. 2 is a side elevational view, the opposite side being a mirror image thereof; and,

FIG. 3 is a front elevational view thereof.

The views of the furniture leg not shown form no part of the claimed design. The broken lines depicting a portion of a table represent environmental elements only and form no part of the claimed design.
